UNITED STATES PATENT OFFICE

140,108

DESIGN FOR A VARIABLE ELECTRICAL CONDENSER

Reginald Thomas Nutter, Chesham Bois, and
Francis Robert Lord, Terriers, High Wycombe,
England, assignors to Ingersoll Limited, High
Wycombe, England, a British company

Application August 1, 1944, Serial No. 114,680
In Great Britain March 22, 1944

Term of patent 14 years

(Cl. D26—1)

To all whom it may concern:

Be it known that we, Reginald Thomas Nutter, a subject of the King of England, residing at Orchard House, North Road, Chesham Bois, Buckinghamshire, England, and Francis Robert Lord, a subject of the King of England, residing at 24, Geralds Road, Terriers, High Wycombe, Buckinghamshire, England, have invented a new, original, and ornamental Design for a Variable Electrical Condenser, of which the following is a

specification, reference being had to the accompanying drawing, forming part thereof.

The figure is a front perspective view of the variable electrical condenser showing our new design.

We claim:

The ornamental design for a variable electrical condenser, as shown.

REGINALD THOMAS NUTTER,
FRANCIS ROBERT LORD.
